UNITED STATES PATENT OFFICE.

DUNCAN C. HESS, OF CHESTER, PENNSYLVANIA, ASSIGNOR TO WESTINGHOUSE ELECTRIC AND MANUFACTURING COMPANY, A CORPORATION OF PENNSYLVANIA.

AUXILIARY RAM FOR STOKERS.

Application filed July 5, 1922. Serial No. 572,903.

The invention relates to mechanical stokers of the underfeed type, and it has as an object to provide an auxiliary ram for stokers of the character designated which shall effect a more complete combustion of that portion of the fuel bed which passes from the rear ends of the retorts to the refuse grates. It has for a further object to maintain at a relatively low temperature those portions of the auxiliary ram which become under certain conditions of operation exposed to the heat of the burning fuel.

These and other objects are effected by my invention, as will be apparent from the following description and claims taken in connection with the accompanying drawings, forming a part of this application, in which:

Fig. 1 is a fragmentary view in longitudinal section of an overfeed stoker embodying my invention;

Fig. 2 is a view in rear elevation of the auxiliary ram;

Fig. 3 is an enlarged view in longitudinal section of the auxiliary ram; and,

Fig. 4 is the fragmentary plan view of the stoker illustrated in Fig. 1, the ram being removed from the retort at the right to show the openings therein.

In the operation of stokers at the overload capacities employed in central power stations, it has been found that the portions of the residue passing out through the retorts contain a higher percentage of unconsumed fuel than the portions discharged from the twyer sections, and that, when the fuel is fed to the furnace in such manner as to secure substantially complete combustion of this fuel discharged from the retorts, the auxiliary rams are heated to such a high temperature as to cause them to burn out after relatively short periods of service.

The purpose of the present invention is to remedy these deficiencies by providing means for securing at overload capacities reasonably complete combustion of the fuel discharged from the retorts and to protect the auxiliary rams from destructively high temperatures under all operating conditions. This is accomplished by constructing the auxiliary rams with a plurality of hollow pushing members and causing air under pressure to pass through the hollow members into the fuel in the retorts. The con-

struction serves a two-fold purpose; it facilitates combustion in zones having a considerable unconsumed fuel content and it cools the metallic portions of the ram, which are exposed to heat, sufficiently to prevent a burning out of these members.

Referring to the drawing, I show in Fig. 1 an underfeed stoker of a conventional type, composed of alternately arranged retorts and twyer sections. The stoker retorts and twyers may be of any of the well known underfeed stoker constructions, the present invention being in no wise limited to the specific structure of the underfeed stoker. As illustrated, the stoker comprises twyer boxes 11, supported upon suitable frame work 12, and carrying twyer members 13. The twyer boxes 11 are spaced to form the side walls of retorts 14, which, as shown, include bottom plates 15, deflector members 16 and a coal plate 17. As illustrated, the retorts 14 are of decreasing depth from the front to the rear of the furnace. A hopper 18 is provided at the front of the furnace from which the fuel is fed through the passage 19 by means of the usual reciprocating ram (not shown). Overfeed sections 21 are provided at the rear of the stoker, which may be of any well known construction, in the present drawing, an oscillating section being illustrated. Air under pressure is fed to the chamber 22 beneath the retorts and twyer boxes in the usual manner, as through a conduit 23 provided with a valve 24.

An auxiliary ram 30 is disposed in each retort and is adapted to be reciprocated therein by means of a rod 31 connected to the driving mechanism of the stoker (not shown). As illustrated in Fig. 3, the ram comprises a base plate 32 to which is attached a depending lug 33 connected to the rod 31 for transmitting reciprocatory motion to the ram. A plurality of demountable pusher members 35, 36 and 37 of box-like construction and carried by the base plate 32 and form therewith the hollow ram 30. The pusher members 35, 36 and 37 are provided with air ports, 38, 39 and 40 respectively. The ports are located in the upper portion of the rear face of each pusher member and are preferably inclined downwardly to prevent the clogging thereof with fuel.

The auxiliary ram 30 slides upon the bottom plate 15 of the retort, a slot 42 being

provided for the movement of the lug 33. The retort member 15 is provided with a plurality of spaced ports 43, 44 and 45. The base plate 32 of the ram is provided with a plurality of spaced ports 46, 47 and 48 which are adapted to register with ports 43, 44 and 45 respectively, thereby providing a means for admitting air at all times to the interior portions of the pushers 35, 36 and 37 respectively. It will be observed that the ports 46 in the rearward pusher member 35, are larger in area than the ports 47 in the intermediate pusher member 36, and that ports 47 are larger in area than the ports 48 in the forward pusher member 37. The purpose of the different size ports is to supply air for combustion in increasing amounts from the front to the rear of the stoker for the reason that more air for cooling the pusher members and for supporting combustion is required where the greatest amount of active combustion is present.

The operation of the above described structure is as follows: The fuel is forced 25 into the retort through the passage 19 and elevated to cover the twyers 13 by means of the deflector plate 16. The auxiliary ram 30 is reciprocated to agitate and break up the partially coked fuel as it approaches the rear 30 of the stoker and to push rearwardly the residue of the fuel onto the overfeed grates 21. In this operation, the nose of the pusher members may be subjected to the heat of the furnace and of the burning refuse in such 35 manner as to cause a rapid deterioration of these elements. To effect a cooling of these elements, air under pressure is admitted into the interior of the ram 30 from the chamber 22 through the registering openings 43, 46, 40 44, 47 and 45, 48 and discharged through ports 38, 39, 40 into the burning fuel where it assists in the combustion of the unconsumed portions of the refuse being delivered to the overfeed grates 21. A cooling 45 of the auxiliary pusher and a more complete combustion of fuel consequently results.

While I have shown my invention in several forms, it will be obvious to those skilled in the art that it is not so limited, but is 50 susceptible of various other changes and modifications without departing from the spirit thereof, and I desire, therefore, that

only such limitations shall be placed thereupon as are imposed by the prior art or as are specifically set forth in the appended 55 claims.

What I claim is:

1. In combination in an underfeed stoker, a fuel feeding retort, an auxiliary ram in the retort, said auxiliary ram comprising a plurality of hollow, step-like pusher members, each of said pusher members having a port disposed to deliver air into the fuel bed, said retort and said pusher members each being provided with a series of openings, the openings of said retort registering with the openings of said pusher member, the openings of at least one series being of graduated size. 70
2. In an underfeed stoker, an air box, a fuel feeding retort extending rearwardly from the front of the stoker and provided with a plurality of openings in its bottom communicating with the air box, an auxiliary ram structure in the retort comprising a plurality of box-like pusher members adapted to slide on the retort bottom, each of said members being provided with air openings for discharging air into the fuel in the direction of fuel feed and with openings registering with the openings in the retort bottom, the openings registering with the openings in the retort bottom being larger in area in the rearward pusher member than in the forward pusher members. 75
3. In an underfeed stoker, an air box, a fuel feeding retort extending rearwardly from the front of the stoker and provided with a plurality of openings in its bottom communicating with the air box, an auxiliary ram structure in the retort comprising a plurality of box-like pusher members adapted to slide on the retort bottom, each of said members being provided with air openings for discharging air into the fuel in the direction of fuel feed and with openings registering with the openings in the retort bottom, the openings in the pusher members registering with the openings in the retort bottom progressively increasing in area from front to rear. 80

In testimony whereof, I have hereunto subscribed my name this 29th day of June, 1922.

DUNCAN C. HESS.
